(57) **CLAIM**

The ornamental design for a toilet seat cover, as shown and described.

DESCRIPTION

FIG. 1 is a top front side perspective view of a toilet seat cover showing my new design;

FIG. 2 is a top view of the toilet seat cover;

FIG. 3 is a bottom view of the toilet seat cover;

FIG. 4 is a right side view of the toilet seat cover;

FIG. 5 is a left side view of the toilet seat cover;

FIG. 6 is a front view of the toilet seat cover; and,

FIG. 7 is a rear view of the toilet seat cover.

The broken lines are illustrative of portions of the article forming no part of the claimed design.
